Pennis, Davis, Marvin & Edwards

UNITED STATES PATENT OFFICE.

GRANT HOERNER, OF NEW YORK, N. Y.

HOLDER FOR PAPER-BOUND BOOKS.

Application filed February 23, 1921. Serial No. 447,084.

To all whom it may concern:

Be it known that I, GRANT HOERNER, residing at New York, in the county of New York, State of New York, have invented 5 certain new and useful Improvements in Holders for Paper-Bound Books; and I do hereby declare the following to be a full, clear, and exact description of the invention, such as will enable others skilled in the art 10 to which it appertains to make and use the same.

This invention relates to holders or backs for paper-bound books.

Paper-bound books, particularly those 15 which are large and bulky and at the same time cheaply made, as, for example, most telephone directories, do not stand up well under usage. The backs often become broken and the leaves loosened in consequence. More than this it is common practice 20 to hang such books when not in use by means of a string passing through a hole in the upper left hand corner of the book. This further tends to distort the book and 25 entails the necessity of drilling a hole through the entire book.

Temporary holders for magazines, newspapers, loose leaves, etc., are, of course, old, but none of these is adapted for use in connection 30 with the heavier type of paper bound books, such, for example, as telephone directories. A holder for such a book should hold the back and adjacent edges so that twisting will be avoided even when the 35 book is hung; it should provide a substantial support for the book when hung; and it should provide positive means for securing the book in place in the holder free from any possibility of working loose. In addition 40 it is desirable that the holder be made adjustable to fit books of different depths of binding and different thicknesses. It is, therefore, the object of the present invention to design a holder of this nature, particularly 45 adapted for heavy paper bound books.

This object has been attained by the provision 50 of a shallow box designed to receive the back of the book and prevent its twisting out of shape and breaking. The width of the box is made approximately the width of the book, although an absolutely tight fit is not essential, and the back of the book is designed to lie in contact with the bottom 55 of the box. The longitudinal side walls or flanges of the box are not intended to press upon the book with sufficient force to hold

the latter in place, but merely so to confine the book so that in cooperation with the bottom of the box distortion will be largely prevented. The holding function is performed by a longitudinal thin strip which is held by the end walls or flanges of the box and passes between the pages of the books. Such a strip is readily placed in operative position and is readily removed. Its use necessitates no permanent alteration whatever in the book itself. In order to provide for books of different thicknesses the box can be made of telescoping parts so that the longitudinal sides or flanges can be moved 60 relative to each other, and in order to provide for books of different depths of binding the end walls can be so constructed that the retaining strip may be moved relative to the bottom of the box.

The invention will be more clearly understood after a study of the accompanying drawing illustrating a preferred embodiment of the invention. In this drawing Fig. 1 is a side elevation of the holder showing a book held therein; Fig. 2 is a front elevation of the holder itself showing the means for securing the telescoping members in adjusted position; Fig. 3 is a detail view of the longitudinal metallic strip 75 which is inserted between the leaves of the book; Fig. 4 is a section on an enlarged scale taken along line 4—4 of Fig. 1; Fig. 5 is a plan view of the holder looking downwardly upon it as shown in Fig. 1; and Fig. 6 is a section likewise on an enlarged scale taken along line 6—6 of Fig. 1 and showing the holder in extended position but without showing the book.

In this drawing 1 represents an adjustable holder. This holder comprises two interfitting or telescoping members 2 and 3, each provided with upstanding longitudinal flanges 4 and 5 respectively. These flanges bear against the covers of the book adjacent its back and are commonly made about one-half or five-eighths of an inch in height. If substantially less than this they are inadequate to hold the back of the book firmly and prevent its twisting and breaking and if much more than this they interfere with the reading of the book, as the printing often extends to within one-half inch of the back.

Member 2 is provided at each end with 110 forwardly extending ends walls or plates 6 and 7, which are substantially greater in

height than the flanges 4 and 5. Member 3 is provided with end flanges 8 and 9 of substantially the same height as the longitudinal side flanges 2 and 3.

5 Member 3 slides over the face of member 2 and between end plates 6 and 7, as is clearly shown in Fig. 2. The distance between flanges 4 and 5, which is adjustable to fit any given book, is fixed when the desired 10 adjustment has been attained by means of two clamping members 12 and 13, which are pivoted to member 2 and are bent to pass over and lie upon the face of member 3. Each of these clamping members is provided 15 with a longitudinal slot 14 in each of which headed pins 15 riveted to the member 3 are designed to move. Each slot 14 is provided with a series of notches 16 which receive the shank of pin 15 and hold it firmly. The 20 number of these notches may be varied so that the degree of adjustment may be made as fine as is desired.

Each of the end plates 6 and 7 is provided with a plurality of slots 17 and 18. 25 These slots are designed to hold a longitudinal metallic strip 19, which is inserted between the pages of the book. This strip, as shown most clearly in Fig. 3, is provided with notches 20 adjacent each end, these 30 notches enabling it to be held in the slots 17 or 18 without longitudinal displacement but without interfering with lateral movement. This strip may be held in either 35 set of slots 17 or 18, depending upon the depth of the binding of the book to be held. The upper end of the strip is provided with a ring 21 by means of which both book and holder may be suspended.

The above described holder is used as 40 follows: When it is desired to secure a large paper-bound book, such as a telephone directory, within the holder, the strip 19 is first removed by twisting it so that it may be pulled through the slots which hold it, the 45 members 2 and 3 are then extended a sufficient width so that the flanges 4 and 5 will bear firmly upon the covers of the book and the members clamped in this adjusted position by means of clamping pieces 12 and 13. 50 The book is then inserted and opened and strip 19 is placed between its central leaves.

The position of the retaining strip when 55 in use is normally beyond the outer edges of the side walls of the box. If the box is made deep it will interfere with the use of the book, and if the retaining strip is placed too close to the binding it may tend to break the back of the book. For these two reasons the end walls or plates are 60 preferably made higher than the side walls. When the book and holder are hung from

ring 22 the weight of the book is carried directly by the lower end plates 7 and 8. The position of the parts is clearly indicated by Fig. 4.

65

By making the members 2 and 3 adjustable relative to each other books of varying thicknesses can be accommodated and by reason of the slots 17 and 18 the metallic strip 19 may always be positioned between 70 the central leaves of the book. Moreover, by employing a plurality of such slots the distance of this strip 19 from the back of the book may be varied so that books of varying depths of binding may be readily 75 held.

80

The parts of this holder may be readily made from sheet metal and stamped to shape. The result is a cheap and durable, as well as useful, article.

Although one preferred embodiment of the invention has been shown and described it is to be distinctly understood that the invention in its broadest aspects is not limited to these details of construction. For example, 85 clamping means of other designs might be employed and other means developed for securing the adjustability of the retaining strip both laterally and forwardly of the back. Such modifications are to be considered as fairly embraced within the spirit 90 of this invention, which is limited only by the scope of the appended claims.

I claim:

1. A holder for paper-bound books comprising a shallow box receiving the back of the book and preventing its twisting, said box having relatively narrow longitudinal side walls or flanges and relatively wider end walls, and a longitudinal retaining strip 95 held by the end walls beyond the outer edges of the side walls and passing between the pages of the book to hold it within the box.

100

2. A holder for paper-bound books comprising a pair of telescoping back members, longitudinal flanges on said back members designed to bear against the book, means for holding said back members in adjusted position to fix the distance between the flanges, and a longitudinal retaining strip 105 designed to pass between the pages of the book and secure it in the holder.

110

3. A holder for paper-bound books comprising two telescoping back members, a notched and slotted clamping piece on one of said back members, and a pin on the other, the pin slideable in the slot and designed to be held by one of the notches to fix the relative position of the two back members.

115

In testimony whereof I affix my signature.
GRANT HOERNER.
